(57) **CLAIM**

The ornamental design of connected cards, as shown and described.

DESCRIPTION

FIG. 1 is a front elevational view of the connected cards of my new design, the rear elevational view is a mirror image thereof;

FIG. 2 is a side elevational view thereof, the opposite side elevational view is a mirror image thereof;

FIG. 3 is a top plan view thereof;

FIG. 4 is a bottom plan view thereof;

FIG. 5 is a front elevational view of a first modification of the connected cards of FIG. 1, the rear elevational view is a mirror image thereof;

FIG. 6 is a side elevational view of FIG. 5, the opposite side elevational view is a mirror image thereof;

FIG. 7 is a top plan view of FIG. 5, the bottom plan view is a mirror image thereof;

FIG. 8 is a bottom plan view of the second tier from the bottom of the connected cards;

FIG. 9 is a front elevational view of a second modification of the connected cards of FIG. 1, the rear elevational view is a mirror image thereof;

FIG. 10, is a side elevational view of FIG. 9, the opposite side elevational view is a mirror image thereof;

FIG. 11 is a top plan view of FIG. 9;

FIG. 12 is a bottom plan view of FIG. 9;

FIG. 13 is a front elevational view of a third modification of the connected cards of FIG. 1, the rear elevational view is a mirror image thereof;

FIG. 14 is a side elevational view of FIG. 13, the opposite side elevational view is a mirror image thereof;

FIG. 15 is a top plan view of FIG. 13, the bottom plan view is a mirror image thereof; and,

FIG. 16 is a bottom plan view of the second tier from the bottom of the connected cards.
